CLAIM

We claim the ornamental design for a handle, as shown and described.

DESCRIPTION

FIG. 1 is a perspective view of a handle showing our new design, the broken lines being for illustrative purposes only and forming no part of the claimed design;

FIG. 2 is an enlarged front end elevational view of FIG. 1; FIG. 3 is an enlarged rear end elevational view of FIG. 1; FIG. 4 is an enlarged side elevational view of FIG. 1; FIG. 5 is an enlarged top plan view of FIG. 1; and, FIG. 6 is an enlarged bottom plan view of FIG. 1.
